LIGHT FIXTURE FOR SUSPENDED GRID CEILING

John T. Bibb, La Canada, Calif., assignor to Tok-Products Co., Los Angeles, Calif., a corporation of California
Filed June 2, 1958, Ser. No. 739,425
11 Claims. (Cl. 174—71)

This invention relates to a suspended ceiling and more specifically to a light installation for such a ceiling.

It has heretofore been the practice to construct ceilings using various types of grid installations wherein squares of acoustical board or similar sections are supported between the grid work. In such installations the positioning of lights and their size has been seriously restricted. Recessed fixtures have been resorted to but external lighting fixtures have presented a difficult problem.

It is, therefore, an object of this invention to provide novel means for installing lights in a suspended ceiling.

It is still a further object of this invention to provide such means which are extremely economical and easily installed to avoid affecting the cost of installation of such a ceiling.

It is still a further object of this invention to provide wireways positioned above the ceiling which strengthen the ceiling structure as well as shield the wiring and preserve the standard modular size of the grid pattern.

It is still a further object of this invention to provide suitable means by which a lighting fixture may be suspended from the ceiling at any point along one of the runners or at an intersection of runners and which also shields the wiring.

Other objects and advantages will be readily apparent from the following description.

In the drawings:

FIGURE 1 is a perspective view of a segment of ceiling embodying this invention.

FIGURE 2 is a section taken along line 2—2 of FIGURE 1.

FIGURE 3 is a section taken along line 3—3 of FIGURE 2.

FIGURE 4 is a section taken along line 4—4 of FIGURE 2.

FIGURE 5 is a perspective view of a half of the wire box.

FIGURE 6 is a perspective view of a modified form of this invention.

FIGURE 7 is a view taken along line 7—7 of FIGURE 6.

FIGURE 8 is a section taken along line 8—8 of FIGURE 6.

This application is a continuation-in-part of my prior co-pending application Serial Number 579,230 entitled "Light Fixture for Suspended Grid Ceiling" now abandoned.

A typical grid installation is partially illustrated in FIGURE 1 and comprises spaced parallel runners 10 and 12, which are inverted T-shaped and may be formed from extruded aluminum. These runners are interconnected by runners such as 14 in this embodiment normal to runners 10 and 12 and of similar construction and extended between runners 10 and 12. A clip 16 connects runner 14 to a similar runner 18 on the other side of runner 12 through which the clip passes. The bottom

2

flanges of the T-shaped runners form a support for ceiling forming members 20, in this instance an acoustical board. In this manner the complete ceiling may be formed as squares similar to 20 supported between runners 10 and 12 and spaced parallel runners such as 14. The ceiling thus formed is suspended by suitable wires 22 from the framework of the building. The wires are suitably spaced over the area of the ceiling and are attached to the runners 10 and 12 by means of clips 24 bolted to the runners. Such a ceiling is well known in the art and is rather briefly described to aid in understanding the description of the lighting system with which this invention is concerned.

15 A U-shaped channel 26 has on its underside a groove formed receiving the upper edge of the inverted T-shaped runner 10. A depending flange 28 is bolted to the runner by bolts 30. A cover 32 is provided at the upper end of channel 26 forming a housing for the electrical wiring 34.

20 The cover 32 terminates at the split wire box 36. This box may be positioned anywhere along the runner 10 even at the point of intersection with runners 14 and 38.

25 The box 36 is formed of two separate halves 40 and 42. The top of each half has a pair of opposed ears 44 and 46 by means of which the two halves are held together. The top 48 of the wire box thus formed is above the open portion of U-shaped channel 26 so that the wires 34 pass out of the channel 26 into the wire box 36. Each half 40 and 42 has notches such as 50, 52 and 54 cut therein on either side so that they will fit flush against the runner 10, flange 28 and channel 26. The top 32 terminates at and is flush with the box 36 at the junction of the two halves. Each half at its lower extremity rests upon the inturned flanges of the T-shaped runners. Each half also has formed therein a tunnel such as 56 which terminates flush with the runner 10, flange 28 and channel 26, being notched as are the side walls of each half at 50, 52 and 54. The tunnel thus formed on either side of the runner 10 receives the cross runners 14 and 38 permitting the wire box to be stationed at an intersection of runners if desired.

30 The tunnels 56 also support the wires 34 in wire box 36 over which they are trained after leaving channel 26. As best seen in FIGURES 1 and 4 the corners of the wire box 36 extend beyond the flanges of the runners permitting wires 34 to pass below the runners through spaces 58. At each corner the wire box 36 has an ear 60 through which the wire box is bolted to the support box 62 for the light fixture 64. The wires 34 pass into box 62 through suitable openings therein aligned with openings 58. The light fixture is then wired as is well known in the art. In these drawings the light fixture represents one-half of a fixture for a fluorescent light although any suitable light fixture may be used.

35 To add rigidity to the structure a cross bolt 65 may be provided adjacent the underside or base of the wire box 36. This bolt passes through a suitable bore in runner 10 similar to bore 66 in runner 12 and is suitably held from the exterior of the wire box halves.

40 A modification of the runner 10 and channel 26 may be utilized wherein the two parts are extruded as an integral piece in place of bolting same together.

45 In operation a U-shaped channel 26 is mounted upon

a runner 10 wherever it is desired to mount a light fixture. A pair of wire box halves 40 and 42 are positioned between sections of the covers 32 for the channel 26. The electrical wiring 34 housed in channel 26 is brought through the wire box formed by bolting the halves 40 and 42 together. The wire passes over the tunnels formed in the halves and through openings 58 at the base thereof. The light box 62 is bolted to the corners of the wiring box and the wires 34 enter the light box and are appropriately connected.

Referring now to FIGURES 6 through 8, a modified form of this invention is illustrated wherein like parts are given a similar designation with the addition of the exponent "a." It is apparent that this embodiment differs primarily from that previously described in the formation of the wire box 68. The box is formed of complementary halves 70 and 72 which extend from within light box 62a, which has a suitable aperture therein to receive same, above the wire supporting member or runner 26a. The halves of the wire box are secured together by rivets 74 in complementary ears 76. The box thus formed has a gooseneck 78 at its upper extremity provided with suitable grooves to receive beads 80 on the upper edge of runner 26a. Covers 32a on either side of gooseneck 78 fit snugly thereagainst so that wire 34a supported in channel 26a may pass through wire box 68 downwardly into light box 62a which is bolted onto the lower flange of runner 10a.

In this embodiment channel 26a has a series of depending flanges 82 punched therefrom which abut one side of the upstanding leg of runner 10a and a series of loops 84 punched therefrom which support set screws 86 which bear against the other side of said leg to clamp channel 26a thereon. An enlarged bead 88 is formed at the extremity of the upstanding leg runner 10a to provide a more secure junction.

While what hereinbefore has been described as the preferred embodiment of this invention, it is readily apparent that alterations and modifications can be resorted to without departing from the scope of this invention and such alterations and modifications are intended to be included within the scope of the appended claims.

I claim:

1. In a ceiling of the type having flanged runners supporting removable ceiling forming members the combination of: a wire supporting member extending along one of said runners, a wire box extending from the flange of said runner to said wire supporting member enclosing a wire received from said wire supporting member to below said flange.

2. In a ceiling of the type having flanged runners supporting removable ceiling forming members the combination of: an enclosed wire supporting member mounted on one of said runners, a hollow wire box extending from the flanges of said runner and enclosing a portion of said wire supporting member, means communicating the interior of said wire box with the interior of that portion of the wire supporting member enclosed within said box.

3. In a ceiling of the type having flanged runners supporting removable ceiling forming members the combination of: a wire supporting channel mounted on one of said runners, a hollow wire box slotted to snugly fit said runner, said box extending from the flange of said runner upwardly and over a portion of the top of said channel.

4. In a ceiling of the type having flanged runners supporting removable ceiling forming members the combination of: a wire supporting channel mounted on one of said runners, a hollow wire box slotted to snugly fit said runner, said box extending from the flange of said runner upwardly and over a portion of the top of said channel and cover means enclosing the portions of said channel projecting outside said wire box.

5. In a ceiling of the type having flanged runners supporting removable ceiling forming members the com-

bination of: a wire supporting channel mounted on one of said runners, a hollow wire box slotted to snugly fit said runner, said box extending from the flange of said runner upwardly and over a portion of the top of said channel and cover means enclosing the portions of said channel projecting outside said wire box, the lower extremity of said box being open on the underside of said runner.

6. In a ceiling of the type having flanged runners supporting removable ceiling forming members the combination of: a U-shaped wire supporting channel having depending flanges receiving the upper portion of one of said runners, the upper edges of said channel having outwardly projecting beads formed thereon, a wire box having grooves therein adapted to receive said beads securing said box on said channel, said wire box extending downwardly from said channel and being open from the underside of said runner.

7. In a ceiling of the type having flanged runners supporting removable ceiling forming members the combination of: a U-shaped wire supporting channel having depending flanges receiving the upper portion of one of said runners, the upper edges of said channel having outwardly projecting beads formed thereon, a wire box having grooves therein adapted to receive said beads securing said box on said channel, said wire box extending downwardly from said channel and being open from the underside of said runner and cover plates grooved to receive said beads on said channel and abut either side of said wire box to completely enclose a wire reeved through said channel and said wire box so that said wire is accessible beneath said ceiling.

8. In a ceiling of the type having flanged runners supporting removable ceiling forming members the combination of: a U-shaped wire supporting channel having depending flanges receiving the upper portion of one of said runners, the upper edges of said channel having outwardly projecting beads formed thereon, a wire box having grooves therein adapted to receive said beads securing said box on said channel, said wire box extending downwardly from said channel and being open from the underside of said runner, and cover plates grooved to receive said beads on said channel and abut either side of said wire box to completely enclose a wire reeved through said channel and said wire box so that said wire is accessible beneath said ceiling, said wire box being formed of complementary halves facilitating fabrication.

9. In a ceiling of the type having flanged runners supporting removable ceiling forming members the combination of: a wire supporting member having a substantially continuous opening along one side, clamping means on said supporting member along the edges of said opening, means for mounting said supporting member upon one of said runners, a hollow wire box having means for engaging said clamping means at one extremity and having the other extremity accessible from below the flanged runners and cover plates adapted to engage said clamping means and abut either side of said box to close off said opening.

10. In a ceiling of the type having flanged runners supporting removable ceiling forming panels the combination of: a longitudinal wire enclosing member having a substantially continuous opening along one side, means for mounting said enclosing member upon one of said runners, a hollow wire box having attachment means for positioning said box in communication with said substantially continuous opening at one extremity of said box and having the other extremity accessible from below the flanged runners and cover plates adapted to be received by said enclosing member to close off said substantially continuous opening at either side of said box.

11. In a ceiling of the type having flanged runners supporting removable ceiling forming members the combination of: a wire supporting member having a substantially continuous opening along one side, clamping

means on said supporting member along the edges of said opening, means for mounting said supporting member upon one of said runners, a hollow wire box having means for engaging said clamping means at one extremity and having the other extremity accessible from below the flanged runners and cover plates adapted to engage said clamping means and abut either side of said box to close off said opening; a lighting fixture attached to one of said runners on the opposite side thereof from said wire supporting member.

UNITED STATES PATENT OFFICE
CERTIFICATE OF CORRECTION

Patent No. 3,001,001

September 19, 1961

John T. Bibb

It is hereby certified that error appears in the above numbered patent requiring correction and that the said Letters Patent should read as corrected below.

In the grant, lines 2 and 12, and in the heading to the printed specification, lines 3 and 4, for "Tok-Products Co.", each occurrence, read -- Lok-Products Co. --.

Signed and sealed this 6th day of February 1962.
